(No Model.)

J. Z. LEVY.
STREET SWEEPER.

No. 593,749.

Patented Nov. 16, 1897.

UNITED STATES PATENT OFFICE.

JOHN Z. LEVY, OF APOLLO, PENNSYLVANIA.

STREET-SWEEPER.

SPECIFICATION forming part of Letters Patent No. 593,749, dated November 16, 1897.
Application filed June 14, 1897. Serial No. 640,667. (No model.)

To all whom it may concern:

Be it known that I, JOHN Z. LEVY, a citizen of the United States, residing at Apollo, in the county of Armstrong and State of Pennsylvania, have invented certain new and useful Improvements in Street-Sweepers and Conveyers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to certain new and useful improvements in street-sweepers and conveyers.

20 My invention relates to that class of street-sweepers in which the dirt is swept up onto an endless conveyer by a rotatable brush and deposited in a wagon.

25 The invention consists in the novel construction and combination of parts, herein-after fully described and claimed.

30 In describing the invention in detail reference is had to the accompanying drawings, forming a part of this specification, and wherein like numerals designate like parts throughout the several views shown, in which—

35 Figure 1 is a side view of my improved street-sweeper. Fig. 2 is a plan view of the same with the conveyer removed. Fig. 3 is an enlarged perspective view of a portion of the conveyer.

40 In constructing my improved street-sweeper I provide a suitable running-gear for the wagon and which has revolving axles with the wheels made fast thereto, and upon this running-gear I attach a stout frame 1, and upon one side of this frame I secure a pair of hinge-rods 2 and 3, which extend parallel with the frame. Suitable antifriction-rollers 4 are attached to the upper side of the frame and at four different points, and upon these rollers is supported the box-bed 5, which is connected to the said hinge-rods 2 and 3 by the hinge-plates 5'. Attached to the rear end of the wagon-frame and by the links 6 and 7 is the inclined conveyer-pan 8. At the lower end of this pan is formed a pair of upwardly-extended brackets, which support the rotary brush 9. Attached fast to one end of the

55 shaft of the said rotary brush is the gear-pinion 10, and upon the side of the conveyer-pan is formed a bearing, into which is fitted a short shaft 11, and upon this shaft are secured the gear-wheel 12 and chain-wheel 13. The said gear-wheel meshes with the pinion upon the end of the rotary-brush shaft. Upon the rear axle is mounted the chain-wheel 14, and is 60 connected to the chain-wheel 13 at the lower end of the conveyer-pan by means of the chain 15, so as to convey power to the rotary brush and rotate it in an opposite direction when the wagon is moved forward. At the 65 upper end of the conveyer-pan and across the same are loosely fitted a shaft 16, upon which is mounted a pair of spiders 17 and 18, and another shaft 19, which has a similar pair of spiders 20 and 21, mounted thereon. 70 Mounted upon the said spiders is a conveyer, which consists of a series of links 22, 23, and 24, which are all pivotally connected together upon the rods 25. The said links 24 are each turned over at right angles at one end and have secured to them the conveyer-blades 26. 75 Upon the outer end of the shaft 19 is secured a chain-gear 27, and a similar gear 28 is arranged on the end of the rotary-brush shaft and are connected together by the chain 29, 80 in order to transmit power from the brush to the traveling conveyer.

85 The operation of my improved device would be as follows: As the wagon is drawn forward the wheels, by the intermediate gearing, cause the brush to rotate and sweep the material up into the conveyer-pan, where the traveling conveyer catches it and conveys it up to the end of the pan, where it falls into the wagon, and when the wagon has been loaded and 90 transported to the dumps the bed is shoved forward sufficient to clear the conveyer. It is then turned over and the contents dumped out and the bed again placed in position.

95 Slight variations and changes may be made in the detail parts without departing from the general spirit of my invention.

Having thus fully shown and described my invention, what I claim as new, and desire to secure by Letters Patent, is—

100 The combination with a wagon, of the inclined links, the inclined conveyer-pan secured thereto, the transverse shafts at the upper and lower ends thereof provided with

spiders, the endless chain passing around the same provided with blades, the sprocket-pinion on one end of the lower shaft, the sprocket-chain, the rotatable brush having a sprocket-pinion at one end with which said chain engages, the cog-pinion at the other end of said brush, the pinion meshing therewith secured to a stud-shaft, the sprocket-pinion on said stud-shaft, the chain connected therewith and

the sprocket-pinion on the wagon-axle with which said chain is also connected, substantially as described.

In testimony whereof I affix my signature in presence of two witnesses.

JOHN Z. LEVY.

Witnesses:

JOHN GROETZINGER,
GEO. D. KELLY.
